CLAIM

The ornamental design for a case for a mobile communications device, as shown and described.

DESCRIPTION

FIG. 1 is a top plan view of the case for a mobile communications device;

FIG. 2 is a left-side elevation view of the case of FIG. 1;

FIG. 3 is a right-side elevation view of the case of FIG. 1;

FIG. 4 is a front elevation view of the case of FIG. 1;

FIG. 5 is a rear elevation view of the case of FIG. 1;

FIG. 6 is a bottom plan view of the case of FIG. 1;

FIG. 7 is a top, front, right perspective view of the case of FIG. 1; and,

FIG. 8 is a top, back, left perspective view of the case of FIG. 1.

The dashed lines in the figures illustrate portions of the case for a mobile communications device that form no part of the claimed design.

The dot-dash-dot lines adjacent shaded areas in the figures illustrate boundaries of the claimed design.

1 Claim, 4 Drawing Sheets
